[57] CLAIM

The ornamental design for an automotive vehicle body, substantially as shown and described.

DESCRIPTION

FIG. 1 is a front, top and right side perspective view of an automotive vehicle body showing my new design; FIG. 2 is a left side elevational view thereof; FIG. 3 is a top plan view thereof;

FIG. 4 is a front elevational view thereof; and FIG. 5 is a rear elevational view thereof.

The broken lines in the drawing are for illustrative purposes only.
